UNITED STATES PATENT OFFICE

158,019

COVER FOR A BILLFOLD

Samuel J. Smallman, New York, N. Y.

Application November 14, 1949, Serial No. 6,019

Term of patent 14 years

(Cl. D87—3)

To all whom it may concern:

Be it known that I, Samuel J. Smallman, a citizen of the United States of America, residing in New York, county of New York, and State of New York, have invented a new, original, and ornamental Design for a Cover for a Billfold, of which the following is a specification, reference being had to the accompanying drawing, forming part thereof.

Fig. 1 is a plan view of a cover for a billfold, showing my new design.

Fig. 2 is a rear perspective view thereof.

I claim:

The ornamental design for a cover for a billfold, substantially as shown.

SAMUEL J. SMALLMAN.
